[57] CLAIM

The ornamental design for a frame leveler, substantially
as shown and described.

DESCRIPTION

FIG. 1 is a front elevational view of a frame leveler
showing my new design;

FIG. 2 is a rear elevational view thereof;

FIG. 3 is a top plan view thereof;

FIG. 4 is a bottom plan view thereof;

FIG. 5 is a right end elevational view thereof, the left
end elevational view being a mirror image thereof.

FIG.1

FIG.2

FIG.3

FIG.4
